UNITED STATES PATENT OFFICE.

ALFRED J. SHIPLEY, OF WATERBURY, CONNECTICUT, ASSIGNOR TO THE SCOVILL MANUFACTURING COMPANY, OF SAME PLACE.

BUTTON.

SPECIFICATION forming part of Letters Patent No. 230,352, dated July 20, 1880.

Application filed May 19, 1880. (No model.)

To all whom it may concern:

Be it known that I, ALFRED J. SHIPLEY, of Waterbury, in the county of New Haven and State of Connecticut, have invented a new Improvement in Buttons; and I do hereby declare the following, when taken in connection with the accompanying drawings and the letters of reference marked thereon, to be a full, clear, and exact description of the same, which said drawings constitute part of this specification, and represent, in—

Figure 1, face view of the button; Fig. 2, section on line $\alpha\alpha$; Fig. 3, the blank for the front; Fig. 4, perspective view of the inside of the front.

This invention relates to an improvement in that class of buttons for wearing-apparel commonly called "suspender" buttons, the object being to use a light metal and yet give the button sufficient strength at the perforation where it is secured to the garment; and the invention consists in the construction as herein-after described, and particularly recited in the claim.

A represents the front of the button, which consists of a disk cut from sheet metal with a semicircular cut, a , each side the center, leaving the portions thus cut attached to a central part, b , as seen in Fig. 3.

On the under side, and in line with the central portion, b , a piece of wire, d , is laid, and the portions a at each side are turned over and struck onto the said wire, as seen in Figs. 2

and 4, so as to firmly secure it to the disk. Then the back e is placed on the disk and the edge f of the disk or front A is struck down onto the back e in the usual manner, as seen in Fig. 2, the back having a central perforation, h , and may be with or without the rim m around it. This completes the button, and leaves a strong central bar, b , with an opening, m , each side, through which the stitches may be taken or the securing device applied.

The wire d should be a little longer than the diameter of the openings through the disk, and so as to extend onto the surface of the disk, as seen in Fig. 4; but it need be but a little longer than that diameter, because the closing of the portions or lugs a onto it firmly secures it in place.

I do not broadly claim the introduction of a wire bar across the central perforation in a button and between the front and back, as such, I am aware, is not new; but

What I do claim is—
A button composed of the metal front A , having the perforations a cut each side the center, and the wire d arranged between, and the said portions a closed thereon to secure the wire and form the central bar, b , combined with the centrally-perforated back e , substantially as described.

ALFRED J. SHIPLEY.
